US00D760074S

(12) **United States Design Patent**
Giza(10) **Patent No.:** **US D760,074 S**
(45) **Date of Patent:** **** Jun. 28, 2016**(54) **PACKAGE WITH SURFACE
ORNAMENTATION**D190,384 S 5/1961 Meyerson
D191,759 S 11/1961 Meyerson
D195,872 S * 8/1963 Rodriguez D11/24
D352,457 S 11/1994 Hughes et al.(71) Applicant: **S.C. Johnson & Son, Inc.**, Racine, WI
(US)

(Continued)

(72) Inventor: **Danielle C. Giza**, Brooklyn, NY (US)

FOREIGN PATENT DOCUMENTS

(73) Assignee: **S.C. Johnson & Son, Inc.**, Racine, WI
(US)EC 000019690-0005 4/2003
EC 000049390-0001 7/2003(**) Term: **14 Years**

(Continued)

(21) Appl. No.: **29/515,940**(22) Filed: **Jan. 28, 2015**

(51) **LOC (10) Cl.** ..... **09-07**Primary Examiner — Robert M Spear
Assistant Examiner — Darcey E Heflin(52) **U.S. Cl.****CLAIM**(54) **USPC** ..... **D9/434**The ornamental design for package with surface ornamentation,
as shown and described.(58) **Field of Classification Search****DESCRIPTION**USPC D9/434, 441, 447, 457, 643, 667;
D11/24; D14/485, 489; D26/30, 31;
206/557, 775, 776; 215/379, 381, 382;
220/660, 669, 675; 229/87.08, 113.1,
229/123.3, 221FIG. 1 is a front elevational view of a package with surface
ornamentation;CPC G09F 13/18; G09F 13/26
See application file for complete search history.FIG. 2 is a front elevational view showing the package with
surface ornamentation of FIG. 1 in an alternative unclaimed
environment;(56) **References Cited**FIG. 3 is a front elevational view showing the package with
surface ornamentation of FIG. 1 in a second alternative
unclaimed environment; and,

U.S. PATENT DOCUMENTS

FIG. 4 is a front elevational view showing the package with
surface ornamentation of FIG. 1 in a third alternative
unclaimed environment.D74,065 S 12/1927 Lumley
D88,724 S 12/1932 Calvert
D89,100 S 1/1933 White
D92,965 S 8/1934 Kandetzki
